UNITED STATES PATENT OFFICE.

HARRY YARRINGTON ARMSTRONG, OF ELGIN, ILLINOIS.

MECHANISM FOR CUTTING WRAPPERS FROM STRIPS.

979,406.

Specification of Letters Patent. Patented Dec. 27, 1910.

Application filed November 10, 1909. Serial No. 527,193.

To all whom it may concern:

Be it known that I, HARRY YARRINGTON ARMSTRONG, a citizen of the United States, and a resident of Elgin, in the county of 5 Kane and State of Illinois, have invented certain new and useful Improvements in Mechanism for Cutting Wrappers from Strips; and I do hereby declare that the following is a full, clear, and exact description thereof, reference being had to the accompanying drawings, and to the letters of reference marked thereon, which form a part 10 of this specification.

This invention relates to improvements in 15 paper feeding and cutting mechanism for feeding or advancing a strip of paper or like material and cutting individual wrappers or other short sections from the strip.

The invention relates more specifically to 20 means for positioning or locating the strip with respect to the cutting means in such a manner that the predetermined lines along the strip, at which the strip is to be severed, shall be brought accurately into proper cutting 25 alinement with the cutting means.

My invention may be employed wherever 30 it is desired to sever short sections, one at a time, from a continuous strip upon predetermined lines spaced along the strip so that 35 each section will be approximately of the same length as the other sections.

A practical use to which my invention 35 may be put, and for which I have developed it, is cutting wrappers for a gum or like 40 wrapping machine from the advance end of a continuous strip that is fed intermittently to the cutting means and delivering said 45 wrappers to the wrapping mechanism. Such strips are usually previously printed at intervals along their length and the printing is intended to be arranged at uniform 50 distances apart and the strip is cut between the printed areas, so that when the wrappers are cut from the strip, the printing which appears one on each wrapper will be 55 located in a given position on the wrapper and symmetrically with respect to the outlines of the wrapper. It has been found impracticable to so feed a strip to the cutting means that the supposed uniformly spaced 60 printed areas thereon will always appear in proper relation to the cutting means to enable the strip to be always cut on the

proper line between the printed areas. For instance, the feeding means are liable to slip 55 on the strip so that the strip thereby drags behind. When attempt be made, therefore, to feed the strip to the cutting means in timed relation to the operating movements of the latter, the irregularities of the feed 60 of the strip will be evidenced by the lines of severance being brought close to or into the printed areas so that the wrappers or other sections cut from the strip are likely to appear with the printed matter unsym- 65 metrically located thereon, or with only a portion of the printed matter on the wrappers. In order to overcome these defects I propose to employ a locating or positioning device which is arranged to operate on the 70 strip in such a way as to insure that the strip will be presented to the cutting means with the proper points in cutting alinement therewith, regardless of the failure of the feeding mechanism to accurately and positively feed the strip to the cutting means. 75 In order to effect this result, I provide the strip at suitable points along its length with a series of uniformly spaced slits or openings, and provide a locating or jogging device arranged to coöperate with the slotted portions of the strip, said locating device being provided with a finger or projecting part adapted to engage into the slits or openings of the strip in such a way as to advance 80 the strip toward the cutting means independently of the feeding means, when said strip is out of register with the cutting means, the locating device being so arranged on the machine that when it engages 85 the slotted strip to thus advance the same it will bring the strip with its next line of severance into cutting alinement with the cutting means.

As shown in the drawings, Figure 1 is a 95 central vertical section taken through a strip feeding and cutting means, showing a locating or jogging device made in accordance with my invention. Fig. 2 is a vertical sectional view on line 2—2 of Fig. 1, 100 looking in the direction indicated by the arrow. Fig. 3 is an enlarged fragmentary section on the line 3—3 of Fig. 2. Fig. 4 is a fragmentary section on the line 4—4 of Fig. 3. Fig. 5 is a fragmentary section of 105 the strip from which the wrappers or

lengths are cut. Fig. 6 is a fragmentary detail, illustrating a modification of the locating or jogging device.

The feeding and cutting mechanisms by 5 which the strip is advanced and by which the advance end thereof is cut is herein shown as made like the feeding and cutting mechanism illustrated in my co-pending application for United States Letters Patent, filed on the 10th day of November 1909, Serial Number 527,191 said mechanisms being shown as adapted to cut wrappers from a strip and deliver them to the wrapping mechanism of a wrapping machine. Only 15 the essential elements of the feeding and cutting mechanisms are herein illustrated in order to more clearly show the construction to which the present invention more closely relates.

20 The feeding mechanism embraces, in general terms, strip feeding rollers 10, 11 between which the strip *a* is fed, the roller 11 being eccentric with respect to its shaft 12, while the roller 10 is concentric with respect 25 to its shaft 13. The shaft 13 of the concentric roller is mounted in suitable bearings in upright frame members 14, 14 which are suitably secured at their lower ends to the frame 15 of the machine, as shown in 30 said co-pending application. Located below said strip feeding rollers are cutting knives 17, 18, the former being a fixed or stationary knife that is suitably attached at its ends to the frame members 14. The shaft 35 of the eccentric roller and the knife 18 are adapted to be carried by a swinging frame (not shown), movable toward and from the fixed frame members 14, as shown in my aforesaid application. Said fixed and movable frame members are adapted to be vibrated toward and from each other in the manner of jaws to bring the knives into cutting relation, as for instance, by means of an eccentric pinion carried by the shaft 12, 40 which is adapted to mesh with a pinion carried by the shaft 13, one of which pinions is designated as 20 in Fig. 2. Located below said knives 17 and 18 are rollers 22, 23, the shafts 24, 25 of which are mounted in suitable bearings in the lower parts 26 of the frame members 14. Said rollers deliver the sections or wrappers cut from the continuous strip *a* by the knives 17, 18 downwardly into a wrapper recess 27 (when the 45 mechanism is embodied in a wrapping machine) in line with a suitable way or guide 28 through which the articles to be wrapped are adapted to be forced, as by a suitable plunger (not herein shown). The gum or 50 other article thus forced against the wrapper in said recess 27 carries the wrapper into the slot 29 of the wrapping mechanism to effect the first fold of the wrapper about the gum or other article, as set forth in my 55 aforesaid co-pending application. One

roller of each pair of upper and lower rollers is adapted to be driven from a vertical shaft 30, located at one side of the mechanism, through the medium of beveled pinions 31, 32 on the drive shaft which mesh 70 with other beveled pinions 33, 34 on upper and lower roller shafts 13 and 24.

The operation of the feeding and cutting mechanism, so far as above described, is substantially the same as that of the construction set forth in my aforesaid co-pending application, and need not be herein further referred to. It will be understood, however, that the essential features of my invention herein disclosed may be applied to other 80 forms of feeding and cutting mechanisms, arranged to intermittently feed the strip to the cutting means by which to cut the advance end of the strip to produce sections or wrappers of a predetermined length. 85

Referring now to the features of construction constituting the present invention, the same is made as follows: The strip *a* of paper is guided downwardly from an upper roll 35 that is supported on a suitable reel (not shown) that may be mounted on the upper ends of the frame members 14. The said strip is guided from the roll 35 between presser plates 38, 39 one of which is yieldingly pressed against the other, and arranged to afford a light frictional resistance to the passage of the paper between them to the strip feed rollers from the upper reel from which the strip is unwound. The plate 38 is shown as stationary and is fixed to the stationary side members 14 of the frame in any suitable manner. The plate 39, which fits for a portion of its length against the plate 38, is held against the plate 38 by spring pressure. The means herein shown for thus holding the plates yieldingly together consists of screws 41, 41 which extend loosely through the plate 39, near the side margins thereof, into the plate 38, and between the heads of said screws and the plate 39 are interposed spiral, expansively acting springs 42 which act to yieldingly press the plates together. Said springs are made light and afford a slight frictional retardation of the passage of the paper strip between the plates for a purpose hereinafter to be described. The upper end 43 of the spring pressed plate 39 is bent outwardly away from the plate 38 to afford means for supporting any slack in the strip that may occur between this point and the upper roll 35 from which the strip is unwound. 110

Extending rearwardly from the frame members 14, 14 are two arms 45, 45, in the outer upturned ends 46 of which is mounted a rock shaft 47. Extending downwardly from said rock shaft is an arm 48, to the lower end of which is loosely or pivotally connected the rear end of a link 50 that is provided at its forward end with a strap 51 125

which engages an eccentric 52 that is mounted on the shaft 13 of the strip feed roller 10. Extending inwardly from the rock shaft 47 is a second arm 55, the inner end of which 5 arm extends to an opening 56 in the spring-pressed plate 39. Carried by the inner end of said arm, adjacent to said spring-pressed plate, is a pivoted locating or jogging finger 58, the lower end of which extends downwardly and forwardly from the arm 55 and into the opening 56 of the spring-pressed plate. As herein shown said arm 55 is forked at its inner end and the jogging or locating finger 58 is mounted between the 10 fork members on a pivot pin 59 which extends between said arms. The upper end of said finger extends upwardly and rearwardly from its point of pivot and carries a weight 60 which acts, through the lever 20 action of the finger, to exert a pressure of the lower end of said finger against the strip between said pressure plates. A spring pressure device would be the equivalent of the weight and may in some instances be used. 25 The lower end of said locating or jogging finger is provided with a V-shaped recess 60, thereby forming said lower end of the finger with two separated points 61, 62, the outer one, 61 of which is adapted to extend 30 into the slits a' of the strip a to advance said strip, as will hereinafter more fully appear. The inner face of the stationary presser plate 38 is formed, opposite to the opening 56 in the spring-pressed plate with 35 a clearance recess 63 which permits the finger point 61 to pass freely into the slit a' of the strip a .

Located between the presser plates and the roll 35 of paper is an intermittent feed device which acts to withdraw the strip from the roll during the non-feeding movement of the feed rollers 10 and 11 in a manner to produce a looseness or slack a^2 in the strip just above the presser plates, as shown in 40 Fig. 1, so that the only resistance required to move or jog the strip by the finger 58 is that due to the frictional retardation thereof between the plates. If the engagement of the jogging or locating finger with the slotted 45 portion of the strip be depended upon to unwind the strip from the roll 35, the force required to turn the roll might be sufficient to tear the strip. The means for unwinding the strip from the roll consists of a rotating 50 segment 65 having a friction face 66 that cooperates with an idler roller 67 between which and the segment the strip is fed. The shaft 68 of said segment is provided with a 55 beveled pinion 69 which meshes with a pinion 70 on the upper end of the drive shaft 30 whereby said segment is rotated.

In the operation of the mechanism described, the locating or jogging finger moves upwardly and downwardly against the face 65 of the strip at the opening in the movable

presser plate 39 by reason of the connection of its carrying arm 55 with the cam actuated link 50. The said finger presses lightly against the strip and its range of movement along the strip is short. If the feed movement of the strip between the rollers is such as to accurately bring the proper points of the strip into cutting alinement with the knives, the locating finger will move upwardly and downwardly on the strip without any effect to advance the strip. If however the strip should drag behind its proper feeding position, the point 61 of the locating finger will engage into one of the slits a' of the strip when the finger is moving downwardly and act to positively carry the strip a sufficient distance downwardly to properly register the strip with the cutting knives; the engagement of the locating finger with the slotted portion of the strip occurring at 85 the time when the strip is not gripped by the feed rollers and is therefore free to be carried downwardly between the rollers and relatively thereto.

In the form of feeding mechanism as herein shown, the strip is released from feeding engagement with the feeding rollers at the time when the clearance recess 11' of the roller 11 is on the side of the roller shaft adjacent to the companion roller 10, as fully 90 set forth in my aforesaid co-pending application. As herein shown the locating finger is so arranged that, when occupying the lower limit of its movement, it is located a distance from the cutting knives equal to the 95 length of a wrapper or section to be cut from the strip, and the gripping face 11 ^{2} of the roller 11 is of such length that during the intermittent feed of the wrapper between the rollers, which occurs when the gripping 100 face 11 ^{2} of the roller 11 coacts with the roller 10, the slotted portion of the strip previously engaged by the locating finger will be brought into cutting alinement with the knife. It is not essential that the slits a' of 105 the strip a shall be located at the lines of severance in order that such registration of the severance lines with the cutting knives be effected, as said slits may be either above or below said lines of severance, and the 110 locating finger arranged correspondingly above or below the position illustrated in the drawings. The location of the slits at the lines of severance is preferable, however, inasmuch as the slits are lost when the 115 wrappers are severed from the strips. Otherwise said slits would appear in the severed wrappers.

The strip a is frictionally held or retarded 120 between the presser plates 38 and 39 by such light pressure that there will be no tendency to tear the strips at the slits a' when the locating finger engages the same. At the same time the pressure is sufficient to avoid the strip passing too freely toward the knives 130

when not engaged by the gripping face of the roller 11 and when the cutting knives are brought into operation. The pressure brought to bear on the strip above the jogging or locating finger has the effect of keeping the part of the strip which is acted on by the locating finger always under tension so as to insure prompt and ready engagement of the finger with the slits in the strip when brought into line therewith and avoids a slackness in the strip such as would make such engagement of the finger uncertain.

In Fig. 6 is shown a modified form of jogging or locating device, it consisting of a roller element 75 provided on its circumference with one or more teeth or spurs 76 adapted to engage into the slits of the strip. When two teeth or spurs 76 are provided, the roller 75 will be geared to rotate once 20 during each two rotations of the feed rollers.

It will be understood that the mechanism shown may be employed for simultaneously cutting two wrappers from two strips fed downwardly through the guide between the presser plates as, for instance, where an inner, wax paper, wrapper is to be delivered simultaneously with an outer printed wrapper, in both of which the article is to be wrapped. In this arrangement there is no necessity for jogging or locating the unprinted strip so that it will not be slit, but will be fed as it may.

I claim as my invention:

1. A strip feeding and cutting mechanism provided with a jogging device for registering the strip relatively to the cutting means independently of the feeding means.

2. A strip feeding and cutting mechanism arranged to intermittently feed the strip to the cutting means, and intermittently acting means adapted to act on the strip after the advance movement thereof in a manner to advance the strip to the cutting means independently of the feeding means for the purpose of registering the strip with respect to the cutting means.

3. In a machine for the purpose set forth, the combination with cutting means and intermittently acting feeding means, of a jogging device acting on the strip in rear of the feeding means for registering the strip relatively to the cutting means.

4. In a machine for the purpose set forth, the combination with cutting means and intermittently acting feeding means, of a jogging device acting on the strip for registering the strip to the cutting means, and means for maintaining under tension the part of the strip acted upon by the jogging device.

5. In a machine for the purpose set forth, the combination with cutting means and intermittently acting feeding means, of a jogging device having a projection arranged to enter slits in the strip, after the advance

movement of the strip under the action of the feeding means, for further advancing the strip to register the strip relatively to the cutting means.

6. Mechanism for cutting wrappers from a previously printed strip, comprising cutting means, feeding means arranged to alternately advance the strip to the cutting means and release the strip, and registering means acting on the strip when released from the feeding means adapted to advance the strip relatively to the cutting means to register the same.

7. Mechanism for cutting wrappers from a previously printed strip, comprising cutting means, feeding means arranged to alternately advance the strip to the cutting means and to release the strip, and means for jogging the strip relatively to the cutting means when released from the feeding means for registering the same, and means for maintaining under tension the part of the strip engaged by the jogging means.

8. Means for cutting wrappers from a previously printed strip comprising cutting means, means for intermittently advancing the strip to the cutting means and jogging means provided with a projection adapted to engage slits in the strip to advance the strip relatively to the cutting means.

9. Mechanism for cutting wrappers from a previously printed strip, comprising cutting means, means for intermittently advancing the strip to the cutting means, means for tensioning the strip, a jogging device having a projection arranged to enter slits in the tensioned part of the strip to advance the strip toward the cutting means independently of the feeding means and means for feeding the strip from a roll arranged to slack the strip above its tensioned part.

10. Mechanism for cutting wrappers from a previously printed strip, comprising cutting means, means for intermittently advancing the strip to the cutting means, presser members between which the strip is advanced and registering or jogging means acting on the part of the strip between the presser members.

11. Mechanism for cutting wrappers from a previously printed strip, comprising cutting means, means for intermittently advancing the strip to the cutting means, presser members between which the strip is advanced, and a movable jogging device adapted to enter slits in the part of the strip between said presser members for advancing the strip relatively to the feeding means.

12. Mechanism for cutting wrappers from a previously printed strip, comprising cutting means, feed rollers between which the strip is intermittently advanced to the cutting means, and a movable jogging device provided with a projection adapted to bear

against the strip and to enter slits in the strip for advancing it, relatively to the feed rollers, toward the cutting means.

13. Mechanism for cutting wrappers from

5 a previously printed strip, comprising cutting means, feed rollers between which the strip is intermittently advanced to the cutting means, a movable jogging device provided with a projection adapted to bear 70 against the strip and to enter slits in the strip for advancing it, relatively to the feed rollers, toward the cutting means, and an eccentric rotating with one of the feed rollers for actuating said jogging device.

14. Mechanism for cutting wrappers from 15 a previously printed strip, comprising cutting means, feeding means for intermittently advancing the wrapper to the cutting means, means for tensioning the strip, a movable

20 jogging device acting with a light pressure against the tensioned part of the strip and provided with a projection adapted to engage slits in the strip to advance the strip relatively to the feeding means.

15. Mechanism for cutting wrappers from 25 a previously printed strip, comprising cutting means, feeding means for intermittently advancing the wrapper to the cutting means, means for tensioning the strip, a movable

30 jogging device acting with a light pressure against the tensioned part of the strip and provided with a projection adapted to enter slits in the strip to advance the strip relatively to the feeding means, a rocking arm:

35 to which said jogging device is pivoted and means actuated by the feeding means for rocking said arm.

16. Mechanism for cutting wrappers from 40 a previously printed strip, comprising cutting means, feeding means for intermittently advancing the strip to the cutting means, presser plates between which the strip is guided to the feeding means, arranged to maintain the part of the strip

45 between the plates under tension, one of said presser plates being provided with an opening and the other plate being provided opposite to said opening with a recess, and a finger movable along the face of the strip

50 and provided with a projection adapted to enter said opening for engagement with slits in the strip.

17. Mechanism for cutting wrappers from 55 a previously printed strip, comprising cutting means, feeding means for intermittently advancing the strip to the cutting means, means for tensioning the part of the strip in rear of the feeding means, a jogging device movable along the tensioned

60 portion of the strip and adapted to engage slits therein to advance the strip toward the cutting means relatively to the feeding means, and means for unwinding the strip from a roll arranged to form a slack in the

65 strip between the tension means and the roll.

18. Mechanism for cutting wrappers from a previously printed strip, comprising cutting means, feeding means for intermittently advancing the strip to the cutting means, means for tensioning the part of the strip in rear of the feeding means, a jogging device movable along the tensioned portion of the strip and adapted to engage slits therein to advance the strip toward the cutting means relatively to the feeding means, and an intermittently acting device in rear of the tensioning means for unwinding the strip from a roll, the unrolling device acting during the non-feeding period of the feeding means.

19. Mechanism for cutting wrappers from a previously printed strip, comprising cutting means, feed rollers between which the strip is intermittently advanced to the cutting means, presser plates in rear of the feed rollers between which the strip is advanced and by which the strip is tensioned, a jogging device acting against the tensioned portion of the strip for advancing the strip during the non-feeding movement of the feed rollers and means acting during the operation of the jogging device to produce a slack in the strip in rear of the presser plates.

20. Mechanism for cutting wrappers from 95 a previously printed strip, comprising cutting means, feed rollers between which the strip is intermittently advanced to the cutting means, presser plates in rear of the feed rollers between which the strip is advanced and by which the strip is tensioned, 100 a jogging device acting against the tensioned portion of the strip for advancing the strip during the non-feeding movement of the feed rollers and means acting during 105 the operation of the jogging device to produce a slack in the strip in rear of the presser plates, one of the presser plates being provided with a shelf to support the slack portion of the strip.

21. In a strip feeding and cutting mechanism, means for feeding the strip from a roll, operating during a part of the feeding period to quickly draw the strip from the roll faster than it is received by the cutting mechanism and during another portion of said feeding period to release the strip to permit the strip to slack.

22. In a strip feeding and cutting mechanism, feeding means engaging the end of the strip to advance the same and means between said feeding means and the roll from which the strip is unwound for accelerating the unrolling of the strip from the roll beyond the speed at which it is received by the cutting mechanism to thereby slack the strip.

23. In a strip feeding and cutting mechanism, feeding means engaging the end of the strip to advance the same, and a segmen-

tal feed roller intermediate the roll from which the strip is unwound and the main feeding means and engaging the strip in a manner to intermittently accelerate the unrolling of the strip off the roll beyond the speed at which it is received by the cutting mechanism.

In testimony, that I claim the foregoing

as my invention I affix my signature in the presence of two witnesses, this 28th day of 10 September A. D. 1909.

HARRY YARRINGTON ARMSTRONG.
